(57) **CLAIM**

We claim the ornamental design for an electric ice cream scoop, as shown and described.

DESCRIPTION

FIG. 1 is a front perspective view of an electric ice cream scoop showing the present invention, the electric cord strain reliever being shown in phantom and the electric cord being omitted as they form no portion of the ornamental design. FIG. 2 is an enlarged perspective view of a portion of FIG. 1.

FIG. 3 is a bottom plan view of the electric ice cream scoop shown in FIG. 1.

FIG. 4 is a top plan view of the electric ice cream scoop shown in FIG. 1.

FIG. 5 is a side elevation view from the left side of FIG. 4. FIG. 6 is a side elevation view from the right side of FIG. 4.

FIG. 7 is an end elevation view from the bottom of FIG. 4; and,

FIG. 8 is an end elevation view from the top of FIG. 4.
